UNITED STATES PATENT OFFICE.

GEORGE LABARRE, OF NEW ORLEANS, LOUISIANA.

CIGAR-BAND.

959,357.

Specification of Letters Patent. Patented May 24, 1910.

Application filed December 19, 1908. Serial No. 468,354.

To all whom it may concern:

Be it known that I, GEORGE LABARRE, a citizen of the United States, residing at New Orleans, in the parish of Orleans and State of Louisiana, have invented new and useful Improvements in Cigar-Bands, of which the following is a specification.

This invention relates to cigar bands, and particularly to means applied to such a band for severing and stripping it from the cigar.

One object of the invention is to provide a severing device comprising a thread, string or its equivalent secured to the band and having a projecting portion by which it may be manipulated to rupture the band, and which is arranged upon the band in such a manner as to prevent the band from being removed intact from the cigar and reused, thus protecting the maker of a particular brand of cigars from the removal and use of his bands on inferior cigars.

Another object of the invention is to provide a band severing or stripping device by which, in operation, the complete removal of the band from the cigar is insured, and which may be supplied without adding materially to the cost of the bands.

The invention consists of the features of construction, combination and arrangement of parts hereinafter fully described and claimed, reference being had to the accompanying drawings, in which:

Figure 1 is a perspective view of a cigar provided with a band embodying my invention. Fig. 2 is a similar view of the cigar with the band ruptured for removal. Figs. 3 and 4 are inner face views of bands before application, showing different embodiments of the invention.

Referring to the drawings 1 designates a band of conventional form comprising a body portion 2 and reduced ends 3, which latter are adapted to be overlapped and pasted together to apply the band about the cigar. The band may be made of paper or any other similar flexible material, and may bear any suitable advertising matter appropriate to the particular brand of cigar or to the business of the manufacturer. I do not restrict the invention in these particulars.

The band stripper or removing device comprises a thread, strand or strip 4 of any suitable flexible material, such as a length of cord, cotton or other plaited thread, or a length of fine wire, which is arranged transversely on the inner face of the band,

preferably on the body portion 2. As shown in Figs. 3 and 4, one end 5 of the stripper is secured by glue or cement 6 to the inner face of the body portion near one side thereof, and thence extends across said body portion to and beyond its opposite side, the opposite or free end 7 of the stripper projecting sufficiently to be readily grasped between the thumb and forefinger, so that the stripper may be manipulated to sever the body portion transversely and thus rupture the band for removal from the cigar.

The secured end 5 of stripper thread is turned back or curved in the form of a crook or lateral offset which lies on one side of the line of cut of the thread. The advantage of this crooked thread over a straight one is that it will not only sever without tearing through and becoming detached from the band, but remain attached to the band, and remove it entirely from the cigar. In the form of the invention shown in Fig. 3, a finger grip portion 7 is formed by a simple extension of the free end of the stripper without special construction, while in the form shown in Fig. 4, in which the secured end of the stripper 4^a is formed and fastened in the same manner, the free end of said stripper is provided with a knot or tasseled grip 7^a.

In practice, it will be understood that the band will be fastened around the cigar 8 with the secured portion of the stripper lying between the body of the band and the cigar. By this means the stripper will frictionally engage the wrapper of the cigar and serve to prevent removal of the wrapper intact by a sliding movement off either end of the cigar, without injury to the cigar, in the event that the wrapper should not be applied sufficiently tight about the cigar. Hence the removal of wrappers from cigars of one brand and their application by an unscrupulous dealer or person to cigars of an inferior brand will be prevented or greatly deterred. When the band is applied, as shown, the grip portion of the stripper will lie against the cigar beyond the band so that it may be conveniently grasped to manipulate the stripper and rupture and strip the same away from the cigar, as shown in Fig. 2. As the band cannot be removed in any other manner intact, but must be broken to free it from the cigar, the value of the stripper attachment to the manufacturers of high grade cigars, in pre-

venting their bands from being reused by imitators, will be appreciated.

Of course, the stripper, whether in the form of a string or otherwise, may be of 5 an ornamental nature to enhance the attractiveness of appearance of the band, and the crooked or deflected portion may be formed in various ways.

Having thus described my invention what 10 is claimed as new, is:—

1. The combination with a cigar, of a band applied thereto and having an enlarged portion, and a linear stripper arranged transversely beneath the enlarged portion 15 of the band and between the same and the cigar, said stripper extending out of alignment but parallel with the center of said

enlarged portion and having one of its ends bent or deflected laterally and fastened to said enlarged portion in the central line 20 thereof, and having its opposite end projecting beyond the band.

2. The combination with a cigar, of a band applied thereto, and a stripper having a deflected portion secured to the inner side 25 of the band, between said band and the cigar, and a portion projecting beyond the band.

In testimony whereof I affix my signature in presence of two witnesses.

GEORGE LABARRE.
